UNITED STATES PATENT OFFICE.

JOSEPH B. KISLINGER, OF NEW YORK, N. Y.

DESIGN FOR A WATCHCASE.

Application filed May 4, 1926. Serial No. 17,564. Term of patent 14 years.

To all whom it may concern:

Be it known that I, JOSEPH B. KISLINGER, a citizen of the United States, residing in New York city, county and State of New York, have invented a new, original, and ornamental Design for Watchcases, of which the following is a specification, reference being had to the accompanying drawing, forming a part thereof.

Fig. 1 is a front view of a watchcase embodying my design.

Fig. 2 is a side view of the same.

I claim:

The ornamental design for a watchcase substantially as shown.

JOSEPH B. KISLINGER.
